(57) **CLAIM**

The ornamental design for a pitcher, as shown and described.

DESCRIPTION

FIG. 1 is a perspective view showing a pitcher of our new design.

FIG. 2 is an elevational view showing a right side of the pitcher.

FIG. 3 is an elevational view showing a left side of the pitcher.

FIG. 4 is an elevational view showing a front of the pitcher.

FIG. 5 is an elevational view showing a back of the pitcher.

FIG. 6 is a plan view showing a top of the pitcher; and,

FIG. 7 is a plan view showing a bottom of the pitcher.

The broken lines in the drawings are included for the purpose of illustration and form no part of the claimed design.
